Harry Jacobson

UNITED STATES PATENT OFFICE.

SAMUEL WIESENBERG, OF NEW YORK, N. Y.

HORSESHOE.

1,274,483.

Specification of Letters Patent.

Patented Aug. 6, 1918.

Application filed March 26, 1917. Serial No. 157,388.

To all whom it may concern:

Be it known that I, SAMUEL WIESENBERG, a citizen of the United States, and a resident of the city of New York, in the county of Bronx and State of New York, have invented certain new and useful Improvements in Horseshoes, of which the following is a specification.

This invention relates to anti-slipping 10 horseshoes and has for one of its objects the provision of a cheap shoe which can be readily attached over the ordinary shoe or directly to the hoof of a horse, and in which the calks may easily be removed when worn 15 and new ones inserted.

A further object of this invention is the provision of a shoe for holding removable calks firmly in place without danger of losing the calks.

20 A further object of this invention is the provision of a calk which can easily be inserted in place and removed when worn without the use of special tools.

In the type of shoe in which the anti-slipping calks are made integral with the 25 base of the shoe, the entire base must be replaced when the calks are worn out. In the present type in which the calks alone are replaceable, difficulty is usually experienced 30 in removing the old calks and in inserting new ones.

In my improved shoe, the calks are simply slipped into place and are held down against vertical movement by means of a plate and 35 screws, the weight of the horse on the plate acting to prevent relative movement of the parts, as more fully described hereinafter.

In the drawings,

Figure 1 is a perspective view of my improved shoe as it appears when attached to 40 the hoof of a horse.

Fig. 2 is a side view of the shoe, and Fig. 3 a bottom plan view of the same.

Fig. 4 is a partial vertical section showing 45 a rectangular edged calk and the means for holding same in the shoe, and Fig. 5 is a similar view showing a round calk.

Fig. 6 is a bottom plan view of a part of the shoe showing the round calks in place.

50 Fig. 7 is a perspective view of one of my improved rectangular edged calks, and Fig. 8 is a similar view of a round calk.

The metallic angle band 1 is shaped approximately to fit the hoof of the horse and 55 may extend part way or entirely around the hoof, the upstanding flange 2 being adapted

to retain the toe of the hoof therein, the rear end being adapted to prevent slipping of the hoof in the shoe longitudinally. Rectangular or round openings are provided in 60 the horizontal flange or base 3 of said band, depending on whether it is desired to use rectangular edged calks 4 or round calks 5, said openings being made just large enough to receive said calks without play. Both types 65 of calks have flanges 6 thereon to prevent the calk from slipping through the opening in base 3 through which it is inserted. For retaining said calks in place, a plate 7 is placed over flanges 6 (Figs. 4 and 5) and 70 suitably placed screws 8 are used to removably connect plate 7 with base 3. The weight of the horse also tends to hold plate 7 down on said calks when the horse places the shoe on the ground. When the foot is 75 lifted, the tension on screws 8 is sufficient to hold the parts together without relative movement. Any relative movement between the calks, base and plate which may develop may be taken up by tightening screws 8, the 80 adjustment being a simple one and the replacement of any part being unnecessary. Said plate 7 may, if desired, be cut away to avoid friction against the tender portions 85 of the hoof.

Plate hooks 9, placed on each side of the toe, pass through suitable slots 10 in flange 2 of the angle band, said hooks being properly shaped to hold straps 12 therein. A rear hook 13 similarly shaped at its upper 90 end may be formed from or attached to the angle band 1 for holding the rear end of strap 12 away from the hoof. Said strap has the usual buckle 14 thereon for attaching the shoe firmly to the hoof. 95

To remove the calks and to insert new ones, screws 8 are loosened and plate 7 removed from the shoe. The calks may then be lifted out by hand by means of flanges 6. New calks are then inserted in the openings in base 3 provided therefor and plate 7 and screws 8 replaced. It will be seen that the only tool needed for this operation is a screwdriver. 100

What I claim is:

In a horseshoe, an angle band having a horizontal and an upstanding section both having openings therein, removable calks having body portions and flanged heads, said body portions being inserted through the 110 openings in the horizontal section of said angle band and the flanged heads resting

on said horizontal section, means for securing said calks against movement in said shoe comprising a plate resting on the upper surface of the flanges of said calks and in 5 spaced relation to said horizontal section, screws securing said plate to said section for adjusting the space relation of said plate to said section for preventing play between said flanges and said plate and section, hooks

passing through the openings in said up- 10 standing section of said angle band, and means supported by said hooks for securing said shoe to the hoof of an animal.

Signed at the city of New York, in the county of New York and State of New York 15 this 24th day of March, A. D. 1917.

SAMUEL WIESENBERG.
